UNITED STATES PATENT OFFICE.

JOHN A. McDOWELL, OF COLUMBUS, OHIO.

MOVING ADVERTISING APPARATUS.

968,967.

Specification of Letters Patent. Patented Aug. 30, 1910.

Application filed September 27, 1909. Serial No. 519,735.

To all whom it may concern:

Be it known that I, JOHN A. McDOWELL, a citizen of the United States, residing at Columbus, in the county of Franklin and State of Ohio, have invented certain new and useful Improvements in Moving Advertising Apparatus, of which the following is a specification.

My invention relates to the improvement of moving signs of that class in which a plurality of sign or advertising cards are carried by endless belts and displayed through an opening in a casing.

The objects of my invention are to provide an improved sign of this class embodying novel means of supporting the advertising cards or sheets and retaining the latter in their proper positions throughout the movements of the carrying belts; to provide improved means for actuating the carrying belts and to produce other improvements the details of which will be more fully pointed out hereinafter.

These objects I accomplish in the manner illustrated in the accompanying drawing, in which—

Figure 1 is a longitudinal section of an advertising sign casing, showing my improved sign carrying and belt operating mechanism therein, Fig. 2 is an enlarged transverse section on line $x-x$ of Fig. 1, Fig. 3 is an enlarged plan view of the means for imparting rotary motion to the belt carrying rollers, Fig. 4 is an enlarged transverse section through the central portion of one of the belt connecting strips, Fig. 5 is an enlarged face view of one corner of one of the advertising sign sheets or cards, and Fig. 6 is a detail sectional view of a card engaging means hereinafter described.

Similar numerals refer to similar parts throughout the several views.

In carrying out my invention, I employ a suitable oblong casing or housing 1, the latter having its forward side provided with a view opening, in which is supported a plate of glass 2. The casing body 1 is provided with an extension on one end as indicated at 1^a, said extension being separated from the body of the casing by a vertical partition 1^b. In each end of the main casing is journaled a vertical roller body 3, each of these rollers having formed therein adjacent

to each end a peripheral recess or belt-way 3^a, in which recesses are adapted to run parallel endless belts 4 which connect the rollers 3 of the opposite ends of the casing. In forming each of the rollers 3, I also produce therein a comparatively deep peripheral recess 5, the purpose of which will be explained hereinafter. Between the horizontal and parallel portions of each of the belts 4 and extending between the upper and lower sides of the casing 1 is a vertical longitudinal partition 6, the ends of which are adjacent to the inner sides of the rollers 3 and supported from suitable brackets 7 which project from opposite sides of the partitions 6 are vertical track rails or bars 8.

At desirable intervals the upper and lower belts 4 are connected by vertical connecting bars 9, the ends of said bars being preferably riveted in connection with the outer faces of said belts. In the upper portion of each of the bars 9 and on the inner side thereof, is pivoted a suitable form of track wheel 10, these track wheels bearing upon the track bars 8 as indicated more clearly in Fig. 2 of the drawing. In constructing each of the bars 9, I form the upper end thereof with a V-shaped recess 9^a and I connect with one side of each of the bars 9 the central portion of a paper retaining wire 11, the latter extending upwardly and downwardly from a lateral projection of 85 the central portion of each of the bars 9 and having its terminal members bent to the angular form indicated at 11^a in Fig. 4.

12 represents the advertising sheets or cards, which cards are of such height as to cover the otherwise exposed outer face of the upper and lower belts 4. One end of each of these cards overlaps the outer face of one of the bars 9 and the other end thereof extends to within close proximity to the next succeeding bar. The overlapping end of each of the sign cards 12 is held in connection with a bar 9 through the medium of an external bar or binding strip 13, the upper end of each of which has formed therewith a rearwardly projecting pin 14 the enlarged head of which is adapted to be pressed downward into engagement with the V-shaped recess 9^a of the bar 9. The lower end portion of each of the external binding strips 13 are formed with a rearwardly pro-

jecting and downwardly inclined attaching finger 15, which as indicated in Fig. 2 of the drawing, is adapted to engage properly arranged openings in both the sign card 12 and the inner bar 9. As indicated in the drawing, that end portion of each of the sign cards which has its termination adjacent to the bar 9, is held in connection with the outer faces of the belts 4 by the 10 terminal portions of the corresponding spring retaining member 11, said angular terminal portions being inserted through openings in the sign card.

As will readily be understood, the connection of the spring members 11 and the ends of the sign cards is such as to afford a sufficiently yielding engagement of the sign cards and card carrying belts, as to admit of the cards traveling about the end rollers 20 without being subject to undue strain and insuring the retention of said cards in taut conditions. It will be understood that as the belts travel over the journaled rollers 3, the bearing wheels 10 will ride upon the 25 track rails 8 until the ends of said rails are passed; when said track wheels will be carried about the rollers through the recesses 5 on to the track rails on the opposite side of the partition.

30. In order to impart a rotary motion to the rollers 3 and a consequent traveling motion to the belts 4, I have provided a suitable form of motor 16 which is located within the frame extension 1^a of the casing. With 35 the shaft 16^a of the motor, is connected a disk 17 and to this disk is pivoted eccentrically one end of a bar 18, the outer end of the bar 18 being pivoted at 19 to one end of an arm 20 which extends from one end of 40 a suitably journaled vertical shaft 21. The shaft 21 has its upper end portion bearing and extending through the upper side of the casing 1 and above said casing said shaft carries a gear wheel 22. The shaft 21 carries on the underside of the casing top a disk or friction wheel 23 which is formed with an upper side enlargement 23^a. To the arm 20 on the outer side of the wheel 23 is pivoted one end of an operating shoe 24, 45 the remaining end of which has a portion of its surface beveled or inclined, as shown, and its remaining and extended portion curved to conform to the curvature of the wheel 23. The outer end of this operating shoe is 50 held in position to contact with the periphery of the disk 23 through the medium of a spring 25, the outer end of which is connected with one arm of an angular shoe 26, the shoe 26 being pivotally supported 55 from the underside of the casing frame 1 and one arm of said shoe having its end portion partially inclined and partially rounded and adapted to bear against the periphery of the wheel 23. The gear wheel 60

22 gears with a similar gear wheel 27 carried on an end spindle 3^c of one of the rollers 3.

When rotary motion is imparted to the shaft 16^a from the motor 16, it is obvious that a reciprocating motion will be imparted to the bar 18 and arm 20, with the result that an outward swinging movement of said arm 20 will operate through the contact of the extended end portion of the shoe 24 with the periphery of the wheel 23 to impart movement to the latter proportionate to the outward swinging movement of said arm. In the above described movement of the arm, which we will say is in the direction of the arrow indicated in Fig. 3, it is obvious that the pull exerted by the spring 25 on the outer arm of the angular shoe 26, will result in releasing the wheel 23 from frictional contact with the extended portion of the shoe 26, but that on the return movement of the arm 20, the extended curved portion of the shoe 26 will again move into engagement with said wheel and operate as a brake or lock to prevent the reversed rotation of the wheel. In the manner described, a comparatively rapid intermittent rotary motion is imparted to the shaft 21 and wheel 22, which motion is contributed through the gear wheel 27 to one of the belt carrying rollers 3, thereby imparting motion 95 to said roller and to the sign carrying belts.

From the construction and operation which I have described, it will be understood that the various cards which go to make up the continuous sign belt, will be displayed successively through the glass plate 2 and it will also be understood that the sign cards may be readily removed and others substituted therefor, as desired.

From the foregoing description, it will 105 be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claim. 110

115 What I claim, is:

In a moving sign apparatus, the combination with a casing, of vertically disposed rollers journaled in the opposite end portions of said casing, upper and lower belts 120 running about said rollers, bars connecting said belts at intervals, a vertically extending partition in said casing which terminates short of the vertically disposed rollers, horizontal track bars carried by said partition, track wheels journaled upon the belt connecting bars and traveling upon said track bars, clamping bars, members car- 125

ried by said clamping bars for engaging said belt connecting bars, resilient wire, card engaging members, cards, one end of each of said cards being clamped by one of the clamping bars to one of the belt connecting bars and the other end of said card being pierced by one of said resilient wire card engaging members, and means for se-

curing said card engaging member to the next adjacent clamping bar.

In testimony whereof I affix my signature in presence of two witnesses.

JOHN A. McDOWELL.
